UNITED STATES PATENT OFFICE.

ALBERT GREEN REDMOND, OF INDIANAPOLIS, INDIANA, ASSIGNOR TO MARVEL CAR-BURETOR COMPANY, OF FLINT, MICHIGAN, A CORPORATION OF INDIANA.

CHARGE FORMING AND INJECTING DEVICE FOR INTERNAL-COMBUSTION ENGINES.

Application filed March 19, 1920. Serial No. 367,246.

This invention relates to a charge forming and injecting device for internal combustion engines, the object being to provide a device by means of which a very rich mixture of fuel and air can be pumped to the cylinders of the internal combustion engine and injected on the compression stroke in the form of vapor in order to prevent condensation of the fuel through the ordinary manifold now employed in connection with a carburetor.

Another object of the invention is to provide a charge forming and injecting device which is so constructed that the charge of fuel is controlled by a suction controlled valve whereby the opening of the valve will allow fuel to pass into the pumps and be injected into the cylinders, thereby overcoming the difficulties now existing in charge forming devices which depend upon the air to lift the fuel from the jets and carry it to the cylinders.

Another and further object of the invention is to provide a device by means of which the explosive charge in the form of vapor is sprayed into the cylinder just before the ignition, thereby preventing pre-ignition.

A still further object of the invention is to provide a device whereby each cylinder in its order of firing will be supplied with an explosive charge formed of air and fuel so that a perfect combustion will be obtained.

Other and further objects and advantages of the invention will be hereinafter set forth and the novel features thereof defined by the appended claims.

In the drawings,

Figure 1 is a vertical section through a charge forming and injecting device constructed in accordance with my invention. Figure 2 is a section taken on line 2—2 of Figure 1.

In carrying out my invention I employ a float or fuel chamber 1 which is provided with fuel inlet 2 controlled by needle valve 3 through the medium of float 4 of the ordinary construction whereby the fuel will be maintained at a pre-determined level within the fuel chamber. Formed integral with the fuel chamber 1 is a casing 5 having an air inlet 6 and a throttle chamber 7 in which is mounted a throttle valve 8 controlled by a lever 9 in the ordinary manner from the dash of the motor vehicle to which the device is attached. Extending from the throttle

chamber is an induction pipe 10 corresponding to the inlet manifold and through which air is adapted to be admitted to the cylinder through the valves in the ordinary manner.

The casing 5 is provided with a valve seat 11 in which is seated a suction controlled valve 12 which is adapted to be raised off the seat by the suction of the engine in order to allow air to be drawn through inlet 6 into the chamber 13 and out through the throttle chamber. Said valve is held on the seat by spring 14 mounted in a hollow adjusting screw 15 working in the threaded bore 16 formed on the casing whereby the tension of the spring can be adjusted. The valve is provided with a sleeve 17 in which is arranged a lug 18 adapted to receive a suitable instrument inserted through adjusting screw 15 for the purpose hereinafter fully described. The adjusting screw 15 carries a plug 19 for closing the upper end which can be readily removed to allow the instrument to be inserted for rotating the valve. Arranged within the inlet passage is a tubular guideway 20 in which the tubular stem 21 of the valve 12 is slidably mounted for guiding the valve in its vertical movement, said tubular portion communicating with the fuel chamber 1 as clearly shown. The valve stem 21 is provided with a threaded bore 22 in which is adjustably mounted the threaded upper end 23 of needle valve 24 which is adapted to be seated in the valve seat 25 formed in the outlet 26 of the fuel chamber 1 as clearly shown in Figure 1. The valve 24 is provided with a reduced portion 27 preferably rectangular in shape which is slidably mounted in a guide member 28 for preventing the valve from turning and by removing the plug 19 and inserting an instrument through the hollow screw 15 and rotating the valve 12, the needle valve 24 can be adjusted in respect to seat 25 for regulating the outlet of the fuel from the fuel chamber 1.

Extending from the outlet 26 of fuel or float chamber 1 is a passage 29 which communicates with an air well 30 having a calibrated plug 31 through which air is adapted to be drawn so as to mix with the fuel. Extending from the air well or chamber 30 is a passage 32 which communicates with a fuel passage 33. The fuel passage 33 is herein shown formed in the integral extension of the fuel chamber 1 and has a plurality of ver-

tical fuel passages 34 which communicate with a plurality of cylinders 35 mounted on the extension, the fuel passages 34 being controlled by check valves 36.

5 The cylinders 35 herein shown six in number, one for each cylinder of the combustion engine to which it is attached, are enlarged at their upper end as shown at 37 to form the lower portion of the housing, the upper portion 10 being formed by cover 38. Mounted in each of the cylinders 35 is a plunger 39 having a head 40 under which is arranged a coil spring 41, said plunger being herein shown operated by cams 42 carried by shaft 43 15 extending lengthwise through the housing and driven through the medium of suitable driving mechanism from the engine and so timed that the plunger corresponding to the particular cylinder will be operated on the compression stroke so as to inject a charge of fuel into the cylinder as will be hereinafter 20 fully described. The extension in which the pump cylinders are mounted is provided with a plurality of outlets 44, one for each 25 cylinder, each outlet being controlled by a spring pressed check valve 45 and having a coupling member 46 from which extends a pipe 47 extending to each cylinder of the engine and through which the explosive charge 30 formed of fuel and air is forced by the action of the pump so as to inject on the compression stroke a very rich mixture of fuel and air in the form of vapor into the cylinder before the cylinder is fired.

35 In the drawing I have shown six pump cylinders, one for each cylinder of a six-cylinder internal combustion engine and it is of course understood that where the device is used in connection with a four-cylinder internal combustion engine only four cylinders will be employed and when the device is used in connection with an eight-cylinder engine, eight cylinders will be employed, one pump cylinder for each cylinder of the internal 45 combustion engine in order to inject into the cylinder at the start of the compression stroke of the engine a rich mixture of fuel which is timed through suitable gears by the engine so that the charge will be injected 50 at the proper time. I have also shown cams for operating the plungers of the pumps but it is of course understood that these plungers can be operated by any other means desired and I do not wish to limit myself to the details of construction herein shown as my invention consists broadly in providing a fuel injector for injecting an explosive charge into the cylinder which is controlled by suction controlled valve which in turn is controlled 55 by the position of the throttle when the engine is running at high speed. With the throttle open the increased vacuum will allow a greater amount of fuel to pass out of the fuel chamber into the air chamber 60 and be mixed with air from which it will be

drawn by the suction of the pumps and injected into the cylinders of the internal combustion engine.

In the operation of a charge forming and injecting device as herein shown and described, the air for the charge is drawn in by the suction of the engine through the inlet valves, which air controls the position of the suction controlled valve so as to regulate the amount of fuel delivered to the pump cylinders and as the fuel in its passage to the pump cylinder is mixed with air, a very rich mixture in the form of vapor is injected into each cylinder of the internal combustion engine on the start of the compression stroke of the engine.

What I claim is:—

1. A charge forming and injecting device for internal combustion engines comprising a fuel chamber having an outlet, an air passage communicating with the internal combustion engine, a suction controlled valve arranged in said air passage, a valve operated by said suction controlled valve for controlling the outlet of fuel from said fuel chamber and a plurality of pump cylinders communicating with said outlet passage having outlets corresponding to the cylinders of the internal combustion engine for injecting fuel into the cylinders of said engine. 95

2. A charge forming and injecting device for internal combustion engines having a plurality of chambers in communication with the respective cylinders of said engine, means for injecting the explosive charge from said chambers into the cylinders of the engine and means controlled by the suction of the engine for governing the charge delivered thereto. 100

3. A charge forming and injecting device for internal combustion engines having a plurality of pump cylinders provided with conduits leading to the cylinders of the engine, means operated by the engine for operating said pumps for injecting fuel into the cylinders on the compression stroke and means controlled by the suction of the engine for regulating the quantity of fuel delivered to said pump cylinders. 105

4. In a charge forming and injecting device for internal combustion engines, the combination with a reservoir having a valve controlled outlet, an air passage provided with a suction controlled valve for controlling the first mentioned valve, a plurality of pump cylinders, passages extending from the outlet of said reservoir to said pump cylinders and means driven by the engine for operating said pump cylinders for injecting an explosive charge into the cylinders of the engine on the compression stroke. 115

5. A charge forming and injecting device for internal combustion engines having means for injecting an explosive charge formed of fuel and air into the cylinders of 120

125

130

the engine on the compression stroke thereof and means controlled by the suction of the engine for regulating the quantity of fuel delivered to said injecting means.

5 6. A charge forming and injecting device for internal combustion engines comprising a reservoir having a valve controlled outlet, an air passage extending to the induction pipe of the engine provided with a suction controlled valve connected with the valve of said outlet for regulating the passage of fuel therefrom and an injecting means for injecting into the cylinders of the engine on the compression stroke thereof an explosive 70 charge consisting of a mixture of air and fuel.

7. A charge forming and injecting device for internal combustion engines comprising a fuel reservoir having an outlet, a needle valve for controlling the fuel from said reservoir having a suction controlled valve and a plurality of pump cylinders in communication with said fuel outlet for injecting an explosive charge formed of fuel and air into 80 the cylinders of said engine on the compression stroke thereof.

8. A charge forming and injecting device for internal combustion engines comprising a plurality of pumps, means controlled by the suction of the engine for delivering to the cylinders of said pump an explosive charge formed of fuel and air and means operated by the engine for operating said pumps for delivering the explosive charge into the cylinders of the engine on the compression stroke 90 thereof.

9. A charge forming and injecting device for internal combustion engines comprising a casing having an air passage adapted to be connected to the induction pipe of the internal combustion engine, said air passage having a throttle valve mounted therein, a suction controlled valve mounted in said air passage, a fuel chamber having an outlet, a valve 100 mounted to control said outlet, said valve having an adjustable connection with said suction controlled valve, an air chamber in communication with the outlet of said fuel reservoir, a plurality of pump cylinders in communication with said air chamber and a fuel conduit extending from each of said pumps to a cylinder of the internal combustion engine.

10. The combination with an internal combustion engine provided with a plurality of cylinders, of a plurality of pumps having fuel conduits communicating with the respective cylinders, means operated by the engine for operating the pumps at a predetermined time and means controlled by the suction of the engine for regulating the supply of fuel to said pumps.

11. A charge forming device for internal combustion engines having means for vaporizing fuel, a plurality of pumps, means for

delivering fuel to said pumps, means operated by the engine for driving said pumps for injecting the fuel delivered thereto into the respective cylinders of the engine on the compression stroke of the piston and means 70 controlled by the suction of the engine for controlling the amount of fuel delivered to said pumps.

12. The combination with an internal combustion engine provided with a plurality 75 of cylinders and having an intake manifold, a casing provided with an air passage connected to said manifold, said casing being provided with a throttle valve, a suction controlled valve for closing said passage, a fuel chamber having an outlet, a valve mounted in said fuel chamber controlling said outlet, said valve being adjustably connected to said suction controlled valve, an air chamber having a calibrated opening in communication 85 with the outlet of said fuel chamber, a fuel passage in communication with said air chamber, a plurality of pump cylinders in communication with said fuel passage, means driven by the engine for operating said 90 pumps and fuel conduits leading from said pump to the respective cylinder of the engine for delivering a charge of fuel and air to the respective cylinder on the compression stroke of the piston.

13. A charge forming and injecting device for internal combustion engines comprising an injecting device, a device controlled by the suction of the engine for regulating the supply of explosive charge to said injecting 100 device and means timed with the engine for operating said injecting device for delivering the explosive charge to the cylinder of the engine on the compression stroke thereof.

14. A charge forming and injecting device 105 for internal combustion engines having a plurality of pump chambers in communication with the respective cylinders of said engine, said chambers being in communication with the source of fuel supply, pistons working in said pump chambers for injecting the explosive charge from said chambers into the cylinders of the engine and means controlled by the suction of the engine for governing the supply of fuel to said chambers.

15. A charge forming and injecting device for internal combustion engines comprising a casing having an air passage adapted to be connected to the induction pipe of an internal combustion engine, a suction controlled valve mounted in said air passage, a fuel chamber having an outlet, a valve mounted to control said outlet having a connection with said suction controlled valve, an air chamber in communication with the outlet of said fuel reservoir, a plurality of pump cylinders in communication with said air chamber and a fuel conduit extending from each of said pumps to a cylinder of the internal combustion engine.

16. A charge forming and injecting device for internal combustion engines having a plurality of chambers in communication with the respective cylinders of the engine, a preliminary mixing chamber in communication with said chambers, a source of fuel supply, means governed by the suction of the engine for regulating the supply of fuel from the source of supply to said preliminary mixing chamber and pistons mounted in said cylinders for injecting the explosive mixture from said cylinders to the cylinders of the engine.
17. A charge forming an injecting device

for internal combustion engines comprising an injecting device, a preliminary mixing chamber in communication with said injecting device, a device controlled by the suction of the engine for regulating the supply of fuel to said preliminary mixing chamber and means timed with the engine for operating said injecting device for delivering the explosive charge to the cylinders of the engine. 15
